Primary Examiner — Clare E Heflin*(74) Attorney, Agent, or Firm* — Baker Donelson; Dorian B. Kennedy(57) **CLAIM**

The ornamental design for a cold space light, as shown and described.

DESCRIPTION

FIG. 1 is a perspective view of a cold space light showing our new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines depict portions of the cold space light that form no part of the claimed design.
